UNITED STATES PATENT OFFICE.

HYMEN L. LIPMAN, OF PHILADELPHIA, PENNSYLVANIA.

IMPROVEMENT IN EYELETING-MACHINES.

Specification forming part of Letters Patent No. 45,727, dated January 3, 1865.

To all whom it may concern :

Be it known that I, HYMEN L. LIPMAN, of Philadelphia, Pennsylvania, have invented certain Improvements in Eyelet-Machines; and I do hereby declare the following to be a full, clear, and exact description of the same, reference being had to the accompanying drawings, and to the letters of reference marked thereon.

My invention relates to certain improvements, fully described hereinafter, in machines used for attaching eyelets to articles of wearing apparel.

In order to enable others skilled in the art to make and use my invention, I will now proceed to describe its construction and operation.

On reference to the accompanying drawings, which form a part of this specification, Figure 1 is a side view, partly in section, of my improved eyelet machine; Fig. 2, a sectional plan view on the line 12, Fig. 1, and Figs. 3, 4, 5, and 6, diagrams illustrating a part of my invention.

Similar letters refer to similar parts throughout the several views.

A is the frame of the machine, the foundation-plate *a*, which forms a part of the frame, being secured to a bench or table, *v*, and the upper surface of the latter being represented by the line *b*. The frame is of the bent form illustrated in the drawings, and terminates above in the hollow box or casing *B*, and below in the projection *C*, which is situated at a distance above the bench or table *b* for a purpose explained hereinafter.

D and *D'* are two rods or spindles, which pass through and are guided by openings in the lower portion, *c*, of the box or casing *B*, and by openings in a partition situated within the box, and shown by dotted lines in Fig. 1. A coiled spring, *f*, surrounds each spindle, and tends to elevate the same after it has been depressed by the movement of the lever *H*, which is hung to a pin, *h*, passing through the upper end of the box, and which has two arms, (shown by dotted lines), one arm for bearing on each spindle.

In the lower end of each spindle is a hole, in which is cut an internal screw-thread, adapted to the screw-thread on the projection *i* on the upper end of a detachable die, the spindle *D* being thus provided with a detachable die, *E*, and the spindle *D'* with a die, *F*. On the

under side of the die *E* are formed cutting edges, arranged in the form of a cross, Fig. 3, and the lower end of the die *F* has a projection arranged to fit into an eyelet, and a shoulder, *m*, for compressing the same.

A dovetailed recess is cut in the upper surface of the projection *C* for the reception of the plate *G*, which is secured by the set-screw *n*, and in the upper surface of this plate is let a small strip, *q*, of planished brass, to receive the cutting-edges of the die *E*. A hole, *t*, passes through the plate *G* and projection *C*, this hole being central with the die *F*, and being countersunk or recessed at the top for the reception of the flange of the eyelet.

It should be understood that the above-described machine is designed for attaching eyelets to articles of wearing-apparel, whether they be made of textile fabrics, leather, or gum-elastic fabrics.

In using the machine the fabric is in the first instance placed on the plate *G* in such a position that the point where the eyelet has to be inserted shall be directly below the die *E*. The latter, by operating the handle *H*, is then depressed, so as to make in the fabric an incision in the form of the cross, Fig. 3. An eyelet is then placed, flange downward, in the countersink of the plate *G* immediately below the die *F*. The fabric (shown by the red line *x*) is then held up to this die, so that its projection may pass through the fabric at the point where it was severed by the cutting-die *E*, after which the handle *H* is so operated as to depress the die *F*, thereby causing the fabric to pass over the eyelet and compressing the latter and securing it firmly to the fabric.

The ordinary method of securing eyelets to wearing-apparel is to first pierce the latter with a sharp tapering instrument, which disintegrates the fibers of the fabric, distorts the latter, and makes a hole of such a character as to render the insertion of the eyelet a matter of difficulty. The whole operation of securing eyelets by the usual process demands tedious manipulation, which is to a great extent avoided by this portion of my improvement.

It will be understood that the severed portions of the fabric do not appear when the eyelet has been secured, as they are covered by the bent portions of the eyelet when the latter is compressed.

It is not necessary that the cut in the fabric

should in all cases be of the form illustrated in Fig. 3. In many cases the cut may be of the form shown in Fig. 4, or that seen in Figs. 5 or 6; or modified forms of these cuts may be used, according to the nature of the fabric to be operated on and the judgment of the operator. In all cases, however, but little of the fabric should be cut way, the opening for the insertion of the eyelet being made for the most part by merely severing the fabric.

As eyelets of different sizes have to be operated upon, it is important that the dies E and F should admit of being removed, which can be readily accomplished in my improved machine by simply unscrewing them from the spindles. It is also important, for the same reason, that the plate G should be readily detached, which can be done by simply withdrawing the screw n.

By arranging the projection C above the

table many articles of wearing-apparel can be operated upon which could not be reached in the absence of this projection.

I claim as my invention and desire to secure by Letters Patent—

In combination with an eyelet-machine, a die which makes a crucial incision in the fabric for the reception of the eyelet with or without a central excision of a part, leaving the whole or a portion of the material to be embraced by the flange of the eyelet, substantially as shown and described.

In testimony whereof I have signed my name to this specification in the presence of two subscribing witnesses.

HYMEN L. LIPMAN.
